MAIL BOX FOR WALLS

Herbert P. Johnson, Minneapolis, Minn.

Application September 25, 1946, Serial No. 699,221

10 Claims. (Cl. 232—19)

1 This invention relates to a mailbox and particularly to a mailbox adapted to be installed in a wall. Such mailboxes are now used in large numbers in residences, office buildings and other places. Such boxes have an opening at one side of the wall through which the letters or pieces of mail may be passed and also have an opening at the other side of said wall, usually below said first mentioned opening, through which said pieces of mail may be withdrawn.

It is often desirable to install such a mailbox in a wall of a residence or other building after the building has been completed. This usually entails making rather large openings through the wall.

It is an object of this invention to provide a mailbox constructed and arranged to be folded or collapsed into contracted form so that it can be very easily inserted through comparatively small openings in opposite sides of the wall.

It is another object of the invention to provide a mailbox adapted to be installed in a wall comprising a member of flexible, resilient or foldable material, the same preferably being in one integral piece and having a laterally extending upper portion with an open end constructed and arranged to extend through one side of a wall, an intermediate portion extending downwardly from said portion within said wall and a lower laterally extending portion with an open end constructed and arranged to extend through the opposite side of said wall.

It is more specifically an object of the invention to provide such a device as set forth in the preceding paragraph, one or more ends of said member being provided with terminal flanges extending thereabout, together with covers or doors for closing the ends of said member.

It is still further an object of the invention to provide a device such as set forth in the preceding paragraph save one, one laterally extending portion of said member being provided with spaced flanges extending thereabout adapted to be disposed at opposite sides of one portion of a wall, together with lugs of novel form constructed and arranged to hold the trunnions or pintle of a swinging door for closing said portion.

These and other objects and advantages of the invention will be fully set forth in the following description made in connection with the accompanying drawings in which like reference characters refer to similar parts throughout the several views and in which:

Fig. 1 is a view in front elevation of the device;

2

Fig. 2 is a vertical section taken on line 2—2 of Fig. 1, as indicated by the arrows;

Fig. 3 is a partial view in front elevation as seen from the side opposite that shown in Fig. 1;

Fig. 4 is a horizontal section taken on line 4—4 of Fig. 2, as indicated by the arrows;

Fig. 5 is a bottom plan view;

Fig. 6 is a vertical section taken substantially on line 6—6 of Fig. 1, as indicated by the arrows;

Fig. 7 is a partial vertical section taken on line 7—7 of Fig. 3, as indicated by the arrows; and

Fig. 8 is a partial vertical section taken on line 8—8 of Fig. 3, as indicated by the arrows.

Referring to the drawings, a device is shown comprising a member 10. Member 10 will be made of some flexible or foldable material which can be folded, collapsed or contracted into a rather small space and which can be readily unfolded or expanded to assume its normal form. Such material may be resilient although this is not essential to the invention. While member 10 might be otherwise made, in the embodiment

of the invention illustrated it is shown as comprising one integral piece of material. Said member has a passage extending therethrough from one end to the other and is thus generally

20 of tubular form. While the form of member 10 could vary, in the embodiment of the invention illustrated it is shown as substantially rectangular in transverse cross section. The walls of member 10 may be of comparatively small thickness, as shown. Member 10 has an upper laterally extending portion 10a having an open end, said portion being constructed and arranged to

25 extend through an opening in one side 11a of a wall 11, said portion preferably having a terminal flange 10b extending thereabout. The side 11a of said wall is shown as having an inner portion 11b which may comprise the usual studding, laths and plaster and an outer portion 11c which

30 is shown as comprising the usual siding customarily made of overlapping boards. Flange 10b engages the exterior of the outer portion 11c and is overlaid by a plate 12 having an opening therethrough aligning with the open end of portion 10a. Plate 12 will be held in place by suitable

35 nails or screws 13 extending through holes therein into portion 11a. Plate 12 is shown as having its upper portion disposed beneath one of the members of siding 11a. Plate 12 preferably

40 is provided with an inwardly extending flange 12a at its bottom and sides which pro-

jects slightly into the end of portion 10a. Plate 12 at its portion above the opening therein has a part 12b which extends outwardly and downwardly in substantially semi-cylindrical form. A cover or door 14 is provided having inwardly extending lugs 14a bored to receive pintle pins 15 which extend outwardly into lugs 12c formed at the opposite sides of plate 12. While lugs 12c could be variously formed, in the embodiment of the invention illustrated they are preferably bent or pressed in plate 12. Door 14 is thus hinged to plate 12 and its upper end extends somewhat into portion 12b while its lower end engages the outer side of plate 12. Member 10 has a portion 10c which extends inwardly and downwardly from portion 10a and it has an intermediate portion 10d extending downwardly within wall 11 and a lower outwardly extending portion 10e which extends laterally or horizontally outward through the other side 11c of wall 11. The walls of portion 10d are preferably of increased thickness. Side 11c will usually be the inner side of the wall and its exterior will be finished in the usual manner for the interior of a room. At some intermediate part of its length, member 10 is preferably provided with reversely extending folds 10f illustrated as being disposed at portion 10c. Folds 10f are shown as disposed in superposed substantially engaging relation. Member 10 has a bottom portion 10g at the lower part of portion 10d, which bottom portion is preferably provided with an aperture 10h extending through a downwardly projecting lug or boss 10i. Portion 10e is shown as having spaced flanges 10j extending thereabout, the outer one of which is a terminal flange and engages the exterior of wall portion 11c. The other flange engages the opposite side of wall portion 11c. Flanges 10j preferably have spaced ribs 10k extending therebetween. The outer flange 10j also has projecting therefrom spaced lugs 10m. Lugs 10m are provided with substantially cylindrical openings 10n extending therein from their adjacent sides to adjacent the opposite sides thereof and said lugs have slits 10o extending upwardly from openings 10n to the tops of said lugs respectively. A door 17 is provided arranged to close the open end of portion 10e and while this door could be made of various materials, in the embodiment of the invention illustrated it is shown as made of rubber or rubber-like material, the same having a central upwardly extending portion 17a in which is secured a rod or pintle 18 the ends of which extend into openings 10n in lugs 10m. Member 18 may be imbedded in door 17 and the same is shown as having a central portion 18a bent downwardly somewhat. Door 17 has a downwardly extending central portion 17b forming a handle. Door 17 is shown as having a flange at its inner side adjacent its top which engages the outer side of portion 10e and said door has a latch portion 17c adjacent its lower end adapted to extend some distance into portion 10e, the same having a downwardly extending terminal lip adapted to hook over an upwardly extending lug or rib 10p at the bottom of portion 10e.

The member 10 described can be very easily and conveniently installed in the wall. If the same is to be installed in a building already completed, it is only necessary to make openings in portions 11a and 11c of a size to fit portions 10a and 10e. The member 10 can be folded or compressed so as to be contracted as desired and

it can be pushed through the upper opening and then pulled through the lower opening. The flange 10b will be positioned, as shown, and portion 10e can be easily positioned as shown in the opening in portion 11c. Plate 12 can then be placed in position and secured by members 13. Door 14 can then be put into place, one of the pintle pins 15 being inserted in one of the lugs 12c. The other lug 12c which has been bent outwardly will then be brought to the position shown in Fig. 3 and the other pintle pin 15 inserted therein. Door 14 will then be in the position shown in Figs. 2 and 3. Door 17 can easily be placed in position by pressing the ends of member 18 downwardly through the slits 10o into the openings 10n. The opening 10h is provided so that any dust or dirt may pass therethrough as well as any moisture which might collect in member 10 by condensation or otherwise. The folds 10f provide reserve length in member 10 to accommodate different spacings of the openings for portions 10a and 10e.

From the above description it will be seen that I have provided a simple and very efficient structure of mailbox and one which can be very readily installed in a building already completed or in a building while the same is being constructed. The device results in a great saving of time and labor in installing such a mailbox. When installed the device comprises a very desirable and efficient box. The postman can insert the mail by lifting door 14 and the mail will then pass downwardly in member 10 to the bottom thereof where it can be very easily secured and withdrawn by lifting door 17. The portion 17a has sufficient stiffness and resiliency to be held in its closed position by lug or rib 10p and yet it can readily be disengaged from portion 10p by being swung outwardly when taken hold of by its handle 17b. The box is very firmly and securely held in position by the flanges 10j and by plate 12 engaging flange 10b. The device is waterproof and weatherproof and a tight seal is had both at the inner and outer sides of the door. The said seals are not affected or broken by expansion and contraction of the wall due to temperature changes. With the prior metal boxes such expansion and contraction of the wall often results in the formation of cracks about the box which let in cold air. The box and parts used therewith can be very conveniently packed and shipped. It will be apparent that the device will have a high degree of utility for the purpose intended.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A mailbox for installation in a wall having in combination, a member of flexible and foldable material, the same having a passage therethrough and having an upper laterally extended portion with an open end constructed and arranged to extend through one side of a wall, an intermediate portion extending downwardly from said upper portion within said wall and a lower portion extending laterally through the opposite side of said wall and having an open end.

2. A mailbox for installation in a wall having in combination, a member of flexible and foldable material and comprising one integral piece

of said material, said member having a passage therethrough with comparatively thin walls, said member having an upper laterally extending portion with an open end constructed and arranged to extend through one side of a wall, an intermediate portion constructed and arranged vertically within said wall and a lower laterally extending portion having an open end constructed and arranged to extend through the opposite side of said wall.

3. A mailbox for installation in a wall having in combination, a member of flexible and foldable material having a passage therethrough, said member having an upper laterally extending portion with an open end constructed and arranged to extend through one side of a wall, said portion having a terminal flange extending outwardly from its end adapted to engage the outer side of said wall, said member having an intermediate portion extending downwardly within said wall, and a lower laterally extending portion adapted to extend through the opposite side of said wall and having a terminal flange extending thereabout adapted to engage the exterior of said latter side.

4. A mailbox for installation in a wall having in combination, a member of flexible and foldable material having a passage therethrough and having upper and lower portions constructed and arranged respectively to extend through opposite sides of a wall and having open ends, one of said portions having a terminal flange extending thereabout, a plate overlying said flange and secured to the outer side of said wall, said plate having an opening therethrough aligning with the opening in said portion, and a cover for said opening in said plate.

5. The structure set forth in claim 4, said plate having a flange extending into said open end of said portion.

6. A mailbox for installation in a wall having in combination, a member of flexible and foldable material having a passage therethrough and having upper and lower portions constructed and

arranged respectively to extend through opposite sides of a wall and having open ends, one of said portions having spaced flanges extending thereabout adapted to be disposed at and engage opposite sides of one side portion of a wall, and a swinging cover for closing the end of said portion.

7. A mailbox for installation in a wall having in combination, a member of flexible and foldable material having a passage therethrough, said member having an upper laterally extending portion with an open end constructed and arranged to extend through one side of a wall, an inwardly and downwardly extending portion extending from said first mentioned portion, an intermediate downwardly extending portion extending from said second portion, and a lower laterally extending portion constructed and arranged to extend through the opposite side of said wall, said member having a bottom at one side of said last mentioned portion, said bottom having an opening therethrough.

8. The structure set forth in claim 1, said member being folded reversely upon itself with substantially engaging folds intermediate the ends thereof.

9. A mailbox for installation in a wall having in combination, a member of flexible and foldable material having a passage therethrough, said member having upper and lower laterally extending portions with open ends constructed and arranged respectively to extend through opposite sides of a wall, one of said portions having a terminal flange extending thereabout adapted to engage the outer side of said wall, said flange having spaced lugs projecting therefrom with aligned openings for receiving a trunnion, said lugs having slits extending from said openings respectively to the tops of said lugs.

10. The structure set forth in claim 9, a door for closing the open end of said portion having trunnions adapted to be pressed downwardly through said slits into said openings.

HERBERT P. JOHNSON.
